United States Patent

Des. 241,887
Patented Oct. 12, 1976

241,887

MILKING APPARATUS

Robert J. Shulick, St. Charles, Ill., assignor to
Babson Bros. Co., Oak Brook, Ill.

Filed June 13, 1975, Ser. No. 587,214

Term of patent 14 years

Int. Cl. D15—03; D30—99

U.S. Cl. D30—99

FIG. 1

FIG. 2

FIG. 3

FIG. 4

FIG. 5

FIG. 1 is a top plan view of a milking apparatus embodying my new design;

FIG. 2 is a side elevation thereof looking from the left in FIG. 1;

FIG. 3 is a bottom plan view thereof;

FIG. 4 is an end elevation view thereof looking from the left of FIG. 2; and

FIG. 5 is an end elevation view thereof looking from the right of FIG. 1.

The side elevation looking from the right of FIG. 1 is a mirror image of FIG. 2.

I claim:

The ornamental design for a milking apparatus, as shown and described.
